FRANK E. TROUTMAN, OF BUTLER, PENNSYLVANIA, ASSIGNOR TO J. W. CRUIKSHANK
ENGINEERING COMPANY, OF PITTSBURGH, PENNSYLVANIA.

TRACK-ELEVATING MECHANISM.

1,411,315.

Specification of Letters Patent. Patented Apr. 4, 1922.

Application filed May 22, 1920. Serial No. 383,533.

To all whom it may concern:

Be it known that I, FRANK E. TROUTMAN, a citizen of the United States, and resident of Butler, in the county of Butler and State 5 of Pennsylvania, have invented a new and useful Improvement in Track-Elevating Mechanism; and I do hereby declare the following to be a full, clear, and exact description thereof.

10 My invention relates to track elevating mechanism and more particularly to track elevating mechanism adapted for use in connection with apparatus for charging glass furnace pots such as described and claimed 15 in an application filed by me on March 5, 1919, Serial No. 280,839, Letters Patent of the United States No. 1,336,494.

That apparatus consists, generally stated 20 in a suitable frame with a batch supply receptacle carried thereby, a vertical undulating track on said frame, a carriage on said track, and a tiltable ladle mounted on said carriage whereby said ladle may be brought into position to receive the batch 25 from said receptacle advanced into the furnace, and lifted to avoid striking the edges of the pot and then tilted to discharge the batch into said pot. As the above apparatus is used in connection with a furnace where 30 there are a number of different charging openings, and in practice these openings are not of the same height but may vary slightly, the track may not be adapted for directing the ladle properly into all the 35 openings, and it is the object of my present invention to provide means for elevating the track so that a ladle will enter each opening without interference.

In the accompanying drawing, Fig. 1 is 40 a side elevation of my invention shown in connection with the above apparatus, the furnace being shown in section. Fig. 2 is an enlarged detail of the adjustable track section; and Fig. 3 is a cross section of same.

45 In the drawing, the numeral 2 designates an electrically driven trolley arranged to run on the underhung tracks 3 between the girders 4 of a suitable electric crane which spans the furnace room and arranged to 50 travel on the tracks 5. This trolley is also adapted to run over the tracks 3 to the tracks 6 leading to the batch mixer or the storage bin (not shown) for charging the hopper 8 carried by the trolley 2,

55 The frame-work 9 is made of structural

steel properly braced and trussed to give the requisite strength.

Supported in the frame-work 9 are the tracks 10 and 11 parallel with each other and arranged one above the other. The 60 track 11 is provided with inclined portions 12 and 13 and the track 10 with the inclined portions 14 and 15 thereby producing an undulating effect. Furthermore, the upper track 10 extends beyond the track 11 for the 65 purpose more fully hereinafter set forth.

In the track 10 intermediate the portions 14 and 15 is the adjustable or elevating section 16 composed of two parallel rails 17 and 18 fitting down between the stationary 70 track members 19 and 20. Arms 21 are pivotally mounted between the stationary track members 19 and 20 on the bolts 22 passing through said members, the upper ends of said arms bearing against the adjustable rails 17 and 18. The lower ends of the arms 21 are pivotally connected by the bolts 23 to the bars 24. A lever-frame 25 is pivotally mounted on the bolts 26 passing through the stationary track-members 19 75 and 20, the lower ends of said lever being pivotally connected by the bolt 27 to the inner ends of the rails 24. The top member 28 of the lever-frame is of such height as to permit of the passage through said 80 lever-frame of the carriage 29 which is adapted to travel on the tracks 10 and 11, the front wheels 30 of said carriage traveling on the upper track 10, and the rear wheels 31 traveling on the lower track 11. 90 The rails of the track 11 are provided with rack-bars 32 and the pinions 33 mounted on the rear wheels of said carriage engage said rack-bars. A suitable electric motor 34 is provided on the carriage for advancing 95 and withdrawing the same, said motor being connected up with the rear axle to drive the pinions 33.

Mounted on the carriage 29 is the housing 35, said housing being swiveled so as to be 100 free to turn.

Within the housing 34 is a the ladle-shaft 36. A ladle 37 is carried at the forward end of the shaft 36 and at the rear end of said shaft is the bevel-pinion 38 which engages 105 the rack-segment 39 supported by the carriage 29.

Idle-rollers 40 are carried by the housing 35 and said rollers engage opposite sides of the guide-rail 41 on the frame 9. At the 110

forward end of the guide rail 41 is a suitable switch for directing the housing to the right or left according to which pot is to be filled, but it has not been deemed necessary 5 to illustrate this in detail, as it forms no part of the present invention.

The furnace 42 is of the ordinary type with the pots 43 arranged therein and with 10 openings 44, one opening for each two adjacent pots.

When it is desired to charge one of the pots, the trolley 2 is run on to the track 3 and by the electric crane the trolley is moved into position to charge the pots, as indicated 15 in Fig. 1. In order to bring the ladle to the proper height to enter the opening of the furnace without interference in this particular case, the adjustable track section 16 has been elevated by moving the lever-frame 25 to the position indicated in Figs. 1 and 2. By the elevation of this adjustable track section 16, said track section engaging the treads of the front wheels of the carriage, elevates the forward end of the 25 carriage and thereby elevates the ladle. Both track-sections 16 are elevated at the same time by the movement of the lever-frame, and the top member of the lever-frame is elevated to such a height that the 30 carriage is able to pass in under the same.

When the ladle has been advanced into the furnace and swung over the pot, the ladle is tilted to the position indicated in dotted lines Fig. 1 to deliver the batch into 35 the pot.

What I claim is:

1. In apparatus for charging glass furnace pots, the combination with a suitable frame, of a track on said frame, a carriage on said track, a ladle mounted on said carriage, means for advancing and withdrawing said carriage, a movable track-section, interposed in said first-named track and means for raising and lowering said 45 track-section.

2. In apparatus for charging glass furnace pots, the combination of a suitable frame, of a track on said frame, a carriage on said track wheels on said carriage, a 50 ladle mounted on said carriage, means for advancing and withdrawing said carriage,

a movable track-section in the path of the front wheels of said carriage, and means for raising and lowering said track-section.

3. In apparatus for charging glass furnace pots, the combination with a suitable frame, of a track on said frame, a carriage on said track, a ladle mounted on said carriage, a movable track-section comprising parallel members interposed in said first-named track, and means for raising and lowering said members simultaneously. 55

4. In apparatus for charging glass furnace pots, the combination with a suitable frame, of a track on said frame, a carriage on said track, a ladle mounted on said carriage, a movable track-section comprising parallel members, pivotally mounted arms engaging said members, bars connecting said arms, and means for moving said bars simultaneously whereby said track members are raised and lowered. 60

5. In apparatus for charging glass furnace pots, the combination with a suitable frame of a track on said frame, a carriage on said track, a ladle mounted on said carriage, a movable track-section comprising parallel members interposed in said first-named track, elevating mechanism, a lever-frame, connections between said lever-frame and said elevating mechanism whereby said parallel members are raised and lowered simultaneously, said lever-frame spanning said track above said carriage. 75

6. In apparatus for charging glass furnace pots, the combination with a suitable frame, of a track on said frame, a carriage mounted on said track, a tiltable ladle mounted on said carriage, movable track-section comprising parallel members movable up and down in slots formed in said track, elevating mechanism, an operating lever, and connections between said elevating mechanism and said operating lever whereby said members are raised and lowered simultaneously. 85

In testimony whereof, I, the said FRANK E. TROUTMAN, have hereunto set my hand.

FRANK E. TROUTMAN.

Witnesses:
